(57) **CLAIM**

The ornamental design for an audio playing assembly, as shown and described.

DESCRIPTION

FIG. 1 is a perspective view of an audio playing assembly showing our new design;

FIG. 2 is a front elevational view thereof;

FIG. 3 is a rear elevational view thereof;

FIG. 4 is a right side elevational view thereof; the left side being a mirror image thereof;

FIG. 5 is a top elevational view thereof;

FIG. 6 is a bottom elevational view thereof;

FIG. 7 is a front, right side, top perspective view thereof, shown in an environment of use; and,

FIG. 8 is a rear, left side, top perspective view thereof, shown in another environmental use.

The broken lines are shown for environmental purposes only, and form no part of the claimed design.
